UNITED STATES PATENT OFFICE.

ERNEST C. WOODIN, OF CHICAGO, ILLINOIS.

BREEZE-ARRESTOR AND THE LIKE.

1,401,224.

Specification of Letters Patent. Patented Dec. 27, 1921.

Application filed September 27, 1920. Serial No. 413,251.

To all whom it may concern:

Be it known that I, ERNEST C. WOODIN, a citizen of the United States, residing at Chicago, in the county of Cook and State of Illinois, have invented certain new and useful Improvements in Breeze-Arresters and the like, of which the following is a specification.

The present invention has to do with certain improvements in breeze arresters and the like—that is, devices for catching dust and coke breeze and the like delivered from water gas or carbureted water gas machines. In the operation of gas works and many other industrial plants, dust or breeze is discharged from the gas producing machine and fouls the air of the neighborhood. This material eventually finds its way to the ground and to neighboring structures which thereby become fouled, and, as a result, the operation of plants of this type is frequently a public nuisance.

Many arrangements have been devised in the past with the object of arresting and collecting this dust or breeze, not only for the purpose of overcoming the public objection to the operation of the plant, but also for the purpose of making it possible to use this material in industrial processes. As far as I am aware, however, practically all such previous constructions have been open to certain objections or difficulties in operation, because of the fact that they were not properly designed to facilitate the collection of the dust or breeze by properly taking into account the effect of the gas currents on the movement of the individual dust particles. Many of these particles, and, in some plants, practically all of these particles, are of such size that their movements will be controlled not only by the currents of gas, but also by the principles of rebound of discreet particles from the deflecting surface.

One of the objects of the invention is to provide a collector which will insure a proper delivery of the particles into a tank or receiver, while, at the same time, permitting a free delivery of the gas from the chimney or stack which is delivering the breeze. Another object is to so arrange the walls or surfaces of the collecting and conveying tubes that the dust or breeze particles will be enabled to rebound from surface to surface, while, at the same time,

maintaining their general direction of travel toward the receiving or collecting tank.

Other objects and uses of the invention will appear from a detailed description of the same which consists in the features of construction and combinations of parts hereinafter described and claimed.

In the drawing:

Figure 1 shows, in elevation, the general arrangement of the stack and dust or breeze arrester; and

Fig. 2 shows, in enlarged detail, the dust arrester itself.

The chimney or stack is designated by the numeral 3. Ordinarily its upper end 4 is left clear and unobstructed, or, if some type of dust catcher is provided, the same does not permit of a free delivery of the gas from the top end of the stack, while, at the same time, making proper provision for the collection of the dust and breeze.

In carrying into effect the principles of the present invention, I provide a conical hood or the like 5 which I mount above the upper end of the stack, the lower edge 6 of said hood being spaced a suitable distance above the upper edge of the stack to provide a clear opening 7 through which the gas is discharged into the atmosphere. The hood 5 may be supported in a desired position by means of plates 8 secured to the hood and to the stack.

The hood 5 being conical in form is constantly contracted or diminished in diameter until, at its upper end 9, it takes substantially the diameter of the discharge pipe 10. This discharge pipe bends back and down to the point 11 where it, in turn, is still further contracted by a conical connection 12 having a sleeve 13 on its lower end. This sleeve works freely within a socket 14 on the upper end of the breeze pipe 15, the lower end of the breeze pipe extending down into a breeze pocket 16, wherein dust and breeze is collected.

Most of the gas is discharged into the atmosphere from the opening 7, but, in order to permit the travel of a current of gas through the conical arrester 5 and pipe 10, I have provided a revent 17 on the pipe 10 and a revent 18 from the dust pocket 16.

As the gas ascends through the stack 3 at high velocity, the dust and breeze particles will be thrown against the inner and under surface of the conical hood 5. Each

particle so delivered will immediately rebound in accordance with the laws of reflection, so that the angle of deflection will be equal to the angle of incidence. I have shown by the dotted lines 19 the path of travel of a particle of dust or breeze. When the same strikes against the inner surface of the hood on one side, it is deflected off at an angle equal to its angle of incidence and will immediately afterward strike the other side of the inner surface of the hood. Here again it will be deflected at an angle of deflection equal to the angle of incidence. In order to insure that this dust particle will find its way into the pipe 10, it is desirable that no matter how many such strikings and rebounds may take place, each particle will be able to eventually find its way without the necessity of having recourse to a strong gas current, into the pipe 10. It is evident that if the conical hood be constructed with a surface too nearly approximating the horizontal, it will be impossible for the dust particles to find their way into the pipe 10. On the other hand, if the conical surface be formed on an angle very nearly approximating the vertical, it will be evident that the dust particles will very easily find their way into the discharge pipe. I have ascertained the fact that if the surface of the cone be so formed that its elevation has a complete cone is equal to about 2.75 times one-half the diameter of its base, or, if said elevation be greater than its amount, it will be theoretically possible for all of the dust particles traveling straight up the stack to be discharged into the pipe 10 simply by rebounding from surface to surface of the interior of the conical hood, and without even the necessity of using a gas current to assist their movements. Therefore, it is desirable, in every case, to form the conical hood on such an angle that the theoretical difference in elevation between any two rings on its surface shall be equal to about 2.75 times the difference in radius of said rings.

All of the material delivered around the bend 10 of the discharge pipe will find its way by gravity into the pocket 16. Owing to the presence of the revent connections 17 and 18, there will be a certain flow of gas through the pipe 10 which will assist in carrying the dust and breeze particles away from the hood, but, in order to insure a proper delivery of said particles, it is desirable to use the principle hereinbefore explained regarding the angle on which the conical hood should be formed.

While I have in the foregoing description explained the application of the principles in regard to the rebounding of the dust and breeze particles as applied to a conical hood—that is, a hood of circular cross section at every elevation,—still I wish it to be

understood that I do not limit myself to a hood of this or any other cross section. This will be evident when it is considered that the principles governing the rebounding of the dust or breeze particles will be equally applicable to a hood made up from flat surface, provided that each of said surfaces be formed at the proper angle with respect to the horizontal.

An inclined surface which rises approximately 2.75 times the horizontal distance traversed lies at an angle of substantially 70° with respect to the horizontal.

As a simple illustration of one application of the principles of this invention I will mention the following example, but I wish it distinctly understood that in giving this example I do not thereby limit myself to the sizes nor proportions of parts mentioned. With a stack 42 inches in diameter, the diameter of the lower edge of the hood may be made 48 inches, which will give a 3-inch overhang of the hood all the way around. The lower edge of the hood may be spaced from the upper edge of the stack 10 inches, so as to give a 10-inch opening for the discharge of gas. The opening at the upper end of the hood may be made 12 inches in diameter, which will be the size of the discharge pipe 10. Under these conditions the total height of the cone of the hood would be 66 inches, but in view of the fact that the discharge pipe 10 is connected into the hood at a point where the same has a diameter of 12 inches, it follows that the height of the cone up to this point is 49½ inches. With these dimensions the device will be found to operate admirably, and will effectively deliver the dust or breeze particles on the principle of rebounding.

I claim:

1. The combination with a circular stack, of a breeze arrester comprising a continuous conical hood having the angle of its walls at least 60° from the horizontal and unperforated, the base of the hood being at least as great in diameter as the diameter of the stack, means for supporting the hood above the stack and in alinement therewith and with its lower edge spaced above the upper edge of the stack to provide a clear opening for the discharge of gas from the stack into the atmosphere without reversal of direction, a discharge pipe connected to the upper end of the hood centrally thereof, said discharge pipe having a diameter adjacent to the hood at least one-fifth the diameter of the stack, there being no shoulder facing against the upward flow of material at the point of connection of the discharge pipe with the hood, and there being no direct connection from the stack to the discharge connection, substantially as and for the purpose set forth.

2. The combination with a stack, of a

breeze arrester comprising a continuous hood having the angle of its walls at least 60° from the horizontal and unperforated, said hood having its lower end of a size and 5 perimeter to overlie the upper edge of the stack at every point, means for supporting the hood above the stack and in alinement therewith and with its lower edge spaced above the upper edge of the stack to provide 10 a clear opening for the discharge of gas from the stack into the atmosphere without reversal of direction, a discharge pipe

connected to the upper end of the hood centrally thereof, said discharge pipe having a size adjacent to the hood at least one-fifth 15 the linear dimension of the stack measured in the same direction, there being no shoulder facing against the upward flow of material at the point of connection of the discharge pipe with the hood, and there being 20 no direct connection from the stack to the discharge connection, substantially as and for the purpose set forth.

ERNEST C. WOODIN.
